UNITED STATES PATENT OFFICE

JOSEPH BERGER, OF UTICA, NEW YORK, ASSIGNOR TO UNION SPECIAL MACHINE COMPANY, OF CHICAGO, ILLINOIS, A CORPORATION OF ILLINOIS

SEAM FOR SEWED ARTICLES

Application filed December 30, 1929. Serial No. 417,496.

The invention relates to new and useful improvements in seams for sewed articles, and more particularly to a flat seam wherein the fabric sections are joined by stitching threads without any interfolding of the edge portions of the fabric sections.

An object of the invention is to provide an arrangement of stitching threads for a flat seam wherein a plurality of parallel needle thread loops are locked by an equal number of looper thread loops and wherein said thread loops are substantially symmetrically disposed for securing the fabric sections together and also for covering the edges of the fabric sections.

A further object of the invention is to provide a flat seam of the above character wherein an uneven number of needle thread loops are employed.

A further object of the invention is to provide a seam of the above character wherein the looper thread loops extend in the general direction of the length of the seam and laterally toward the center of the seam.

In the drawings:

Figure 1 is a plan view on an enlarged scale, showing more or less diagrammatically the arrangement of the fabric sections and the stitching threads on one face of the seam.

Fig. 2 is a similar view showing the arrangement of the thread loops and fabric sections on the other face of the seam.

Fig. 3 is a diagrammatic view showing the arrangement of the thread loops on the under face of the seam, said thread loops being distorted so as to more clearly show the manner of locking the same.

Fig. 4 is a transverse sectional view through the same on an enlarged scale.

The invention is directed to a flat seam for joining fabric sections. The fabric sections are preferably lapped and are secured by needle thread loops passing through both sections and disposed centrally of the seam.

There is a row of needle thread loops outside of and adjacent the respective edges of the lapped sections. The needle threads are joined by a covering thread on one face of the seam which overlies and covers the edge of one fabric section. Each outer row of

needle thread loops is secured by a looper thread loop and this looper thread loop is expanded and extended so that it is entered by the next formed needle thread loop in its row and also by the needle thread of the center row. The needle thread loops of the center row are secured by the next formed loop in the looper thread of the center row.

Referring more in detail to the drawings, the fabric sections are indicated at F and F'. These fabric sections are lapped as indicated in Fig. 3. The edge of the fabric section F is indicated at f, while the edge of the fabric section F' is indicated at f'. The overlapped fabric sections are secured together by a center row of needle thread loops formed in a needle thread 1. The needle thread loops are indicated at 2. These needle thread loops pass down through the two overlapped fabric sections and are secured beneath the fabric sections by a looper thread 3. This looper thread is formed into thread loops 4 which are passed through the needle thread loops 2.

At one side of the center line of needle thread loops there is a line of needle thread loops formed in a needle thread 5. The needle thread loops of the needle thread 5 are indicated at 6. These loops pass down through the fabric section F adjacent the edge f' of the fabric section F'. A row of needle thread loops 7 formed in the needle thread 8 is passed down through the fabric section F' adjacent the edge f of the fabric section F. A cross thread or covering thread 9 is laid about the needle thread loops in the needle threads 5 and 8 and underneath the needle thread 1.

Thus it is that the needle threads on one face of the seam are connected by a cross thread which serves to cover the edge f of the top lapped portion of fabric F. The needle thread loops 6 on the under face of the seam are secured by a looper thread 10 which is formed into a thread loop 11. The thread loop 11 extends in the general direction of the length of the seam and is extended laterally of the seam so that the next formed needle thread loop 6 passes through the looper thread 11. The next formed needle thread loop 2 also passes through this

100

looper thread loop 11. The looper thread loop 11, therefore, extends inwardly to the center of the seam and covers the edge f' of the fabric section F'.

5 The needle thread loops 7 are secured by a looper thread 12 which is formed into a series of loops 13. These looper thread loops 13 extend in the general direction of the length of the seam and are extending laterally so that each looper thread loop 13 is entered by a needle thread loop 7 and a needle thread loop 2. Here again the looper thread loop extends to the center of the seam. The needle thread loop 2 is passed through first a looper thread loop 13, then a looper thread loop 4 and then a looper thread loop 11 and the needle thread loop 2 is then locked by the next formed looper thread loop 4.

10 It will be seen from the above that the looper threads are symmetrically disposed on the under face of the seam and the seam in transverse section is of uniform construction. The thread loops, as noted, extend in the general direction of the length of the seam, and therefore, loopers may be used for forming the thread loops and passing the same through the needle thread loops which move in the line of feed. These loopers, of course, have a lateral movement and associated with the loopers are spreaders which bring about the concatenation of the thread loops which has been described above. The flat seam has securing threads and covering threads. There are seven threads, three 20 needle threads, three looper threads, and one cross or covering thread.

25 It is obvious that additional rows of needle thread loops may be employed and with each row of needle thread loops an associated looper thread. It is essential, however, that the looper threads shall be carried laterally and locked so as to form a covering seam and a seam which is uniform throughout its transverse extent. It is understood, of course, that the figures of the drawings are on a very large scale in order to show the structure of the seam. The fabric sections are shown as lapped and the edge portions of each lapped section lies substantially in the plane of the fabric sections. Thus it is that the seam is referred to as a flat seam. The edge portions are not interfolded but are joined solely by the stitching threads.

30 Having fully described my invention, what I claim as new and desire to secure by Letters Patent, is:—

35 1. A seam for sewed articles comprising fabric sections having the edge portions thereof lying substantially in the plane of the fabric sections, a center row of needle thread loops, a row of needle thread loops at each side of said center row and spaced therefrom, a covering thread extending about the needle threads in the outer rows and beneath the needle thread in the center row, a looper

thread associated with each row of needle thread loops, the looper threads in the outer rows having their loops extending in the general direction of the length of the seam and also laterally thereof whereby each looper thread loop is entered by the next formed needle thread loop in an outer row and the next formed needle thread loop in the center row, the loops in the looper thread associated with the center row being secured by the next formed needle thread loop in said row.

2. A seam for sewed articles comprising fabric sections having the edge portions thereof lapped, a center row of needle thread loops passing through said lapped portions centrally thereof, a row of needle thread loops outside of and adjacent the edge of each fabric section, a covering thread extending about the needle threads in the outer rows and beneath the needle thread in the center row, a looper thread associated with each row of needle thread loops, the looper threads in the outer rows having their loops extending in the general direction of the length of the seam and also laterally thereof whereby each looper thread loop is entered by the next formed needle thread loop in an outer row and the next formed needle thread loop in the center row, the loops in the looper thread associated with the center row being secured by the next formed needle thread loop in said row.

30 In testimony whereof, I affix my signature.

JOSEPH BERGER.
